UNITED STATES PATENT OFFICE

FREDERICK J. ZIEGLER, OF DECATUR, ILLINOIS

SMOKER'S CONVENIENCE

Application filed June 12, 1931. Serial No. 543,994.

This invention aims to provide a novel means for holding the ashes which fall from a cigarette or cigar, it being possible to set down the holder on a table, without having the holder tip over, and it being possible to close the holder to retain the ashes, so that the holder can be placed in the pocket of a garment.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:—

Figure 1 shows in elevation, a device constructed in accordance with the invention, the article being opened;

Figure 2 is a top plan, wherein the article is shown closed;

Figure 3 is a longitudinal section on the line 3—3 of Figure 2;

Figure 4 is a transverse section on the line 4—4 of Figure 3;

Figure 5 is a fragmental longitudinal section showing a modification.

In carrying out the invention, as disclosed in Figures 1, 2, 3 and 4, there is provided a tray 1 including a trough shaped outer member 2 having guides 3 along its upper edges, the member 2 comprising a short top 4 having upstanding flanges 5 carrying a pivot element 6. The inner end of the member 2 is open as shown at 7, the outer end of the member 2 is closed by a wall 8 carrying an inwardly extended lip 9, and having an upwardly prolonged extension 10 which is joined to the flanges 5.

The tray 1 comprises a trough shaped inner member 11, mounted to slide longitudinally within the outer member 2, the upper edges of the member 11 being slidable in

the guides 3 of the outer member 2, as shown clearly in Figure 4 of the drawing. The trough shaped inner member 11 has an open end 12, and the opposite extremity of the member 11 is closed by a wall 14. The parts 2 and 11 of the tray 1 are telescoped together, as shown in Figure 3. There exists, in the top of the tray, an opening which is marked by the numeral 21. On the outer end wall 14 of the inner member 11 of the tray 1 there is an off set bracket 15 provided in its upper edge with a notch or seat 16.

The numeral 17 marks a mouth piece, provided at its working end with the usual transverse rib 18 which prevents the mouth piece from slipping out of the teeth of the smoker. The mouth piece 17 has a depending wing 19 extended between the flanges 5, the pivot element 6 passing through the wing 19, the mouth piece 17 thus being pivotally connected with the tray 1. On the upper portion of the wing 19 there is a small lug 22.

When the device is opened, as shown in Figure 1, the tray 1 lies below and in front of the mouth piece 17, so as to receive ashes which fall from the cigarette or cigar in the mouth piece. The upper edge of the extension 10 of the wall 8 of the tray engages the rear edge of the wing 19, and, thus, the mouth piece 17 and the tray 1 are held in the position delineated in Figure 1 of the drawing, it being impossible for the tray 1 to swing downwardly on the pivot element 6, below the position shown in that figure.

The inner trough shaped member 11 may be slid to the right in Figures 1, 2 and 3, thereby to accommodate cigars or cigarettes of different lengths. When the mouth piece 17 is folded downwardly and forwardly into the position shown in Figures 2 and 3, the mouth piece forms a complete closure for the opening 21 of the tray, and ashes can not get out of the tray. The user, therefore, can carry the folded article of Figures 2 and 3, in his pocket, without spilling the ashes. The operator can press against the lug 22, and swing the mouth piece 17 upwardly to a partial opened position, from the position of Figures 2 and 3. The lip 9 pre-

vents ashes from finding their way outwardly, to any appreciable extent, along the end wall 8—10 of the tray. When the mouth piece 17 is folded, as shown in Figures 2 and 3, the mouth piece fits in the notch 16 of the bracket 15 on the end wall 14 of the member 11 of the tray 1, and the rib 18, cooperating with the bracket 14, prevents the inner member 11 of the tray from sliding to the right in Figure 1 and opening the tray. The device, therefore, when closed, will securely retain the ashes. The tray 1 is flat on the bottom, and can be set down on a table, without tipping over. Although the longitudinally extensible tray shown in the drawing is highly useful, and an important element of the invention, the tray may be constructed otherwise than as shown and described. The device may be made of any suitable material.

In the modification shown in Figure 5 of the drawing, a different means has been employed for pivotally connecting the mouth piece with the tray. In Figure 5, parts hereinbefore described have been designated by numerals previously used, with the suffix "a." The mouth piece 17a has a hook 20, which engages detachably with the pivot element 6a. Therefore, if the operator wishes, he can take off the mouth piece 17a, and use it alone, without the tray 1a. Aside from the difference in the pivotal mounting shown at 20—6a, the structure of Figure 6 is like the structure shown in Figures 1, 2, 3 and 4 of the drawing.

I claim:—

1. A holder for cigars and cigarettes, comprising a mouth piece, a trough shaped tray located below and at the outer end of the mouth piece, so as to catch the ashes that fall from the article in the mouth piece, and means for pivoting the mouth piece to the tray, at a place near to one end of the tray, the tray having an opening in its top, the mouth piece being as wide as the opening, and at least as long as the opening, whereby when the mouth piece is swung downwardly and forwardly, the mouth piece will completely close the opening and retain the ashes in the tray, when the holder is carried in the pocket.

2. A holder for cigars and cigarettes, comprising a mouth piece, a trough shaped tray located below and at the outer end of the mouth piece, so as to catch the ashes that fall from the article in the mouth piece, the tray being longitudinally extensible, to receive the ashes from cigars and cigarettes of different lengths, the tray comprising slidably telescoped members, means for pivotally mounting the mouth piece on one of said members of the tray and interengaging elements on the mouth piece and on the other of said members of the tray, which coact to hold said members of the tray against relative longitudinal sliding movement, when the mouth

piece is swung downwardly and forwardly upon the tray.

3. The holder for cigars and cigarettes set forth in claim 1, and further characterized by the fact that the means for pivoting the mouth piece to the tray embodies a pivot element carried by the tray, and a hook carried by the mouth piece and releasably engaged around the pivot element.

In testimony that I claim the foregoing as my own, I have hereto affixed by signature.

FREDERICK J. ZIEGLER.
